(57) **CLAIM**

The ornamental design for a target game, as shown and described.

DESCRIPTION

FIG. 1 is a perspective view of a first embodiment of a target game showing the claimed design.

FIG. 2 is a front view thereof.

FIG. 3 is a back view thereof.

FIG. 4 is a right-side view thereof, the left side view thereof being a mirror image of FIG. 4.

FIG. 5 is a top view thereof.

FIG. 6 is a bottom view thereof.

FIG. 7 is a perspective view of a second embodiment of the target game showing the claimed design.

FIG. 8 is a front view thereof.

FIG. 9 is a back view thereof.

FIG. 10 is a perspective view of a third embodiment of the target game showing the claimed design.

FIG. 11 is a front view thereof.

FIG. 12 is a back view thereof.

FIG. 13 is a perspective view of a fourth embodiment of the target game showing the claimed design.

FIG. 14 is a front view thereof.

FIG. 15 is a back view thereof.

FIG. 16 is a perspective view of a fifth embodiment of the target game showing the claimed design.

FIG. 17 is a front view thereof; and,

FIG. 18 is a back view thereof.

The broken lines in the figures show portions of the target game that form no part of the claimed design.

1 Claim, 18 Drawing Sheets
